UNITED STATES PATENT OFFICE.

FREDERICK S. ARTER, OF CLEVELAND, OHIO.

INK-PAD FOR RUBBER STAMPS.

1,114,328.

Specification of Letters Patent. Patented Oct. 20, 1914.

Application filed June 2, 1914. Serial No. 842,359.

To all whom it may concern:

Be it known that I, FREDERICK S. ARTER, citizen of the United States, residing at Cleveland, in the county of Cuyahoga and State of Ohio, have invented certain new and useful Improvements in Ink-Pads for Rubber Stamps, of which the following is a specification.

This invention relates to inking pads for rubber stamps, and has for its object to provide an inking pad of the roller type supported in a box or casing, in which is a metal roller with which the pad roller comes in contact by downward pressure, the lower roller running in the ink contained in the bottom of the receptacle, and the pad roller being supported by springs so that it is out of contact with the metal roller except when the latter is pressed down.

The invention is illustrated in the accompanying drawings, in which:—

Figure 1 is a side elevation of the device. Fig. 2 is a cross section. Fig. 3 is an end elevation. Fig. 4 is a longitudinal section.

Referring specifically to the drawings, 6 indicates an upper roller which may be made of metal or the like, and which is covered by a band or sleeve of felt 7, or similar material, forming a pad. The roller has trunnions 8 which rest on springs 9 contained in housings 10 formed at the end of the well or casing 11 which contains the fluid ink. Slip caps 12 cover the housings 10 and serve to hold the roller in place. The trunnions of the roller 30 extend through slots in the ends of the casing 11. Located within the casing, below the pad roller, is a metal distributor roller 13 which dips into the ink, the trunnions of this roller being mounted in suitable bearing 35 40 censes 14 in the ends of the casing.

Springs 9 normally hold the pad roller out of contact with the conducting roller 13, and by applying a stamp to the pad roller and pressing thereon, the latter is forced down

into contact with the roller 13, and by rotation thereof picks up enough ink to keep the pad roller constantly supplied. The pad roller need not be pressed down into contact with the conducting roller except when additional ink is needed. A cover 15 fits on the 45 casing and incloses the inner parts. The casing can be resupplied with ink at any time by pouring the same therein, and the device will be found much more convenient to use than the ordinary inking pads, which require 50 replenishing at frequent intervals. The use of a pad roller also has this advantage, that any size rubber stamp may be inked uniformly, whereas in the use of the ordinary inking pad, the pad will either have to be 55 made large enough to conform to the size of the rubber stamp or else the stamp will have to be applied to the pad in sections with the result that the ink is not distributed uniformly and a poor impression is made by the 60 stamp.

What I claim as new is:—

An inker for hand stamps, comprising a casing adapted to hold liquid ink and having slots in the ends thereof and housings 70 outside of said slots, a lower roller in the casing adapted to run in the ink, an upper roller pad in the casing having trunnions extending through said slots and movable up and down in said housings, and springs 75 mounted in the housings and pressing against said trunnions, and by which the roller pad is normally supported out of contact with the lower roller, said roller pad being adapted to be pressed down to contact with the lower 80 roller when desired.

In testimony whereof, I affix my signature in presence of two witnesses.

FREDERICK S. ARTER.
